UNITED STATES PATENT OFFICE.

JOSEPH L. HERZOG, OF NEW YORK, N. Y.

DESIGN FOR A FINGER-RING OR SIMILAR ARTICLE.

No. 38,966.

Specification for Design.

Patented Dec. 31, 1907.

Application filed August 14, 1907. Serial No. 388,561. Term of patent 7 years.

To all whom it may concern:

Be it known that I, JOSEPH L. HERZOG, a citizen of the United States, and a resident of New York, borough of Manhattan, in the county of New York and State of New York, have invented a certain new, original, and ornamental Design for Finger-Rings or Similar Articles, of which the following is a specification.

In the accompanying drawing Figure 1 is

a view in side elevation of one side of a ring having my design applied thereto, and Fig. 2 is a similar view of the opposite side thereof.

What I claim is:—

The ornamental design for a finger ring or similar article, as shown.

JOSEPH L. HERZOG.
